FREDERICK J. HEIDEMAN, OF DAYTON, OHIO, ASSIGNEE TO FRIGIDAIRE CORPORATION,
OF DAYTON, OHIO, A CORPORATION OF DELAWARE

REFRIGERATING APPARATUS

Application filed November 30, 1929. Serial No. 410,744.

This invention relates to refrigerating apparatus and more specifically to the condenser or heat dissipating element of refrigerating apparatus.

The principal object of this invention is to increase the efficiency of refrigerating apparatus generally and more specifically to increase the efficiency of refrigerating apparatus by providing a new and improved condenser 10 therefor.

Another object is to provide a condenser of novel construction and design providing a longer path for the fluid to be condensed and an increased radiating surface to conduct the 15 heat from the said fluid while at the same time occupying no more space than heretofore occupied by condensers of much smaller capacity.

Further objects and advantages of the 20 present invention will be apparent from the following description, reference being had to the accompanying drawing, wherein a preferred form of the present invention is clearly shown.

25 In the drawings:

Fig. 1 is a horizontal section through a machinery compartment showing the heat dissipating elements mounted therein;

Fig. 2 is a front view of the compressor 30 and condenser; and

Fig. 3 is a side view of the condenser.

Referring to the drawings and more specifically to Fig. 1 thereof, there is shown generally at 10 a compartment for housing the 35 heat dissipating elements of a refrigerating system. This housing may be part of a refrigerating cabinet and may be located either above or below the insulated food compartment. As shown, this compartment comprises corner post or frame members 11, base members 12, inner and outer side panels 13 and 14, and a front panel 15. For providing access to the interior of the machinery compartment, the front panel 15 is provided with an opening 16 normally closed by the door 17, which may be hinged to the base members 12, as shown at 18. A platform 19 is resiliently mounted within the machinery compartment on the base members 12 and this 45 platform supports the heat dissipating ele-

ments of the apparatus. The refrigerating apparatus herein disclosed to illustrate the invention is of the compression type, the heat dissipating elements of which may comprise a compressor P, a motor M, a condenser C 55 and a receiver R all mounted on the platform 19. The compressor P is provided with a drive shaft 20 on which is mounted a flywheel 21, the spokes of which are formed as fan blades 22. Positioned adjacent to the compressor is a motor M provided with a shaft 23 on which are mounted a pulley 24 and a fan 25. A belt 26 may pass over the pulley 24 and the flywheel 21 to provide a driving connection between the motor and the compressor. The condenser C is located between the compressor P and the flywheel 21 and is connected at its upper end to the discharge side of the compressor by means of the fitting 27 and at its other or lower end is 60 connected to the receiver R by means of the conduit 28. The receiver R is mounted on the platform 19 by means of the brackets 29, and by means of the conduit 30 the receiver is also connected to an evaporator (not 65 shown), but which may preferably be of the flooded type, similar to that shown in the patent to R. G. Osborn, 1,556,708, patented October 13, 1925. The suction side of the compressor may also be connected to the evaporator (not shown), by means of the conduit 70 75 80 85 90 95 100

5 easily supported on the base 19 as shown, by the upright members 36 provided with inclined openings 37 into which the bent ends of the condenser may fit. Also with this type 10 of condenser, the receiver R may be dispensed with by utilizing the lower relatively wide section as the receiver and connecting this section directly to the evaporator, (not shown). Further by bending the conduit 15 into the form shown no openings for the passage of cooling air are provided except through the condenser itself.

15 The condenser, it will be noted, occupies no more space than heretofore occupied by condensers of much smaller capacity and at 20 the same time may be conveniently located between the compressor and the flywheel therefor without sacrificing much condensing surface for the passage of the shaft. Further 25 by bending the condenser as shown first down the right side and then upwardly and down the left side, a plurality of bends equally spaced apart, are presented for the reception of supporting standards as well as for the reception of finned plates if desired.

20 In operation, gaseous refrigerant is withdrawn from the evaporator through conduit 31, compressed by the compressor P into the 25 condenser C when it is liquefied and finally collected in liquid in the receiver R. From the receiver, the liquid refrigerant returns to the evaporator through conduit 30. It will be noted that the back of the compartment 30 is open and air will be drawn inwardly by the fan 23 over the condenser C and striking the front door 17, the air will be deflected and discharged from the compartment by the 35 action of the fan 25. All the condenser surface is thus exposed to the coolest air and does not depend for its cooling, upon air deflected from any hot element of the system.

40 While the condenser has been illustrated as applied to a compression machine assembly it is obvious that the condenser could be used equally well in any other system.

45 While the form of embodiment of the invention as herein disclosed, constitutes a preferred form, it is to be understood that other forms might be adopted, all coming within the scope of the claims which follow.

50 What is claimed is as follows:

55 1. In refrigerating apparatus, a condenser comprising a continuous conduit bent upon itself into a tortuous passage to form upper and lower relatively wide sections and a plurality of relatively narrow intermediate sections, said intermediate sections being spaced apart to provide an opening adapted to receive a 60 drive shaft.

65 2. In refrigerating apparatus, a condenser including upper and lower relatively wide sections and a plurality of relatively narrow intermediate sections, said intermediate sections being spaced to provide an opening

therebetween and all said sections being connected in series relation substantially as described.

3. In refrigerating apparatus, a condenser including a single continuous conduit bent upon itself into a tortuous passage to form upper and lower relatively wide sections and a plurality of relatively narrow intermediate sections spaced apart to provide an opening therebetween, the total width of the relatively narrow sections taken with the space therebetween being substantially equal to the width of the relatively wide sections. 75

4. In refrigerating apparatus, a condenser including a single continuous conduit bent upon itself into a tortuous passage to form a relatively wide section and a plurality of adjacent narrow sections spaced apart to provide an opening therebetween. 80

5. In refrigerating apparatus, a condenser including a single continuous conduit bent upon itself to provide a plurality of parallel passages, said passages being constructed to form a relatively wide section, and a plurality of adjacent relatively narrow sections, said relatively narrow sections being spaced apart 85 to provide an opening therebetween. 90

6. In refrigerating apparatus, a condenser comprising a single continuous conduit bent upon itself to provide a plurality of parallel 95 passages, said passages being constructed to form a relatively wide section, a plurality of adjacent relatively narrow sections, said relatively narrow sections being spaced apart to provide an opening therebetween, and 100 means for supporting the condenser in a vertical position. 105

7. In refrigerating apparatus, a condenser comprising a single continuous conduit bent upon itself to provide a plurality of parallel 110 passages, said passages being constructed to form a relatively wide section, a plurality of adjacent relatively narrow sections and said relatively narrow sections being spaced apart 115 to provide an opening therebetween, and means for supporting the condenser in a vertical position, said supporting means comprising upright metal strips provided with inclined openings for receiving the ends of the condenser. 120

8. In refrigerating apparatus, a condenser including a plurality of horizontal and parallel passages, said passages being arranged to form a relatively wide upper section and a plurality of relatively narrow adjacent sections spaced apart to provide an opening for the passage of a drive shaft. 125

In testimony whereof I hereto affix my signature.

FREDERICK J. HEIDEMAN. 130
